UNITED STATES PATENT OFFICE.

SAMUEL P. WILBUR, OF WILKINSBURG, PENNSYLVANIA, ASSIGNOR TO
WESTINGHOUSE ELECTRIC & MANUFACTURING COMPANY, A COR-
PORATION OF PENNSYLVANIA.

DASH-POT.

No. 821,073.

Specification of Letters Patent.

Patented May 22, 1906.

Application filed April 18, 1905. Serial No. 256,274.

To all whom it may concern:

Be it known that I, SAMUEL P. WILBUR, a citizen of the United States, and a resident of Wilkinsburg, in the county of Allegheny and State of Pennsylvania, have invented a new and useful Improvement in Dash-Pots, of which the following is a specification.

My invention relates to dash-pots, and particularly to dash-pots that are adapted for use in connection with arc-lamps; and it has for its object to provide a dash-pot that shall be simple in construction and effective in operation and shall also be self-lubricating and unaffected by variations in temperature.

15 Dash-pots for use in arc-lamps have heretofore generally been provided with graphite plungers, which were self-lubricating, but were hygroscopic to such degree when cooled after being subjected to the heat of the arc that 20 the low temperatures to which they were often subjected would effect such expansion as to seriously interfere with their operation. This 25 disadvantage is avoided by my invention, which reduces the mass of the plunger by making it of tubular form. Although my 30 invention does not modify the hygroscopic quality of the material, it reduces the mass, and consequently reduces the amount of moisture which can be retained therein, so 35 that wide variations in temperature have no appreciable effect.

The dash-pot of my invention is not restricted to arc-lamp service and may be used for any convenient purpose; but it is specially 35 applicable to service where relatively wide variations in temperature are encountered.

My invention is illustrated in the single figure of the accompanying drawing, which 40 is a sectional elevation of a dash-pot constructed in accordance therewith.

Referring to the drawing, a dash-pot 1 comprises a hollow metal cylinder 2 and a piston or plunger 3, which fits closely in said cylinder. One end of the cylinder 2 is closed by a cap 4, that is provided with a small hole 5, which connects the space between the end of the plunger 3 and the cap 4 with the external air, and a ball-valve 6, that serves to 45 restrict the flow of air through the hole when the piston 3 is moved within its cylinder. The cap 4 is provided with a projection 7, by 50 means of which the cylinder of the dash-pot

may be connected to any desired mechanism. The piston 3 comprises a tubular body portion 8, composed of graphite or similar material having lubricating properties and having beveled edges, end plates or washers 9 and 10, having flanged edges to engage the beveled edges of the body 8, and a screw 11, 55 that projects through the parts 8, 9, and 10 and into the end of a piston-rod 12 and serves to clamp the said parts together and to the end of the rod.

The ball-valve 6 is raised by the air-pressure 65 when the piston 3 is moved toward the cap 4, but is drawn to its seat in the opening when the piston moves in the other direction, so that a partial vacuum is formed in the 70 space between the piston and the cap when the piston is moved in one direction, and the air is compressed therein as the piston is moved in the other direction, so that its motion is retarded in each direction in the usual manner.

I claim as my invention—

1. In a dash-pot, the combination with a cylinder that is open at one end and the other end of which is provided with a cap having a valved opening, of a piston and a connecting-rod attached thereto, said piston comprising a tubular body of lubricating material, end plates, and a screw that clamps the tubular body and end plates together and to the end of the piston-rod and is of materially 85 less diameter than the interior of the tubular body.

2. In a dash-pot, the combination with a cylinder, of a piston comprising a tubular body of lubricating material, end plates or washers and a fastening-screw that clamps the tubular body between the end plates and is of materially less diameter than the interior of the tubular body.

3. In a dash-pot, the combination with a cylinder, of a piston comprising a tubular body of lubricating material having beveled edges, end plates or washers that are flanged to engage the beveled edges of said tubular body, a screw that passes through said washers, and a rod having an end socket to receive said screw.

4. The combination with a cylinder having a cap provided with a valved opening, of a piston comprising a tubular body of graphite and end plates or washers therefor, a rod

and a screw of materially less diameter than the interior of the tubular body for clamping the piston parts together and to the end of said rod.

5. In a dash-pot, the combination with a cylinder, of a piston-rod and a piston comprising a tubular body of graphite, end plates or washers, and a screw of materially less diameter than the interior of the tubular body

for clamping said tubular body and end plates together and to the end of the piston-rod.

In testimony whereof I have hereunto subscribed my name this 15th day of April, 1905.

S. P. WILBUR
